C. F. JOHNSON

CARBURETOR

Filed May 5, 1921

Inventor

Chester F. Johnson.

Attorney

UNITED STATES PATENT OFFICE.

CHESTER F. JOHNSON, OF DETROIT, MICHIGAN.

CARBURETOR.

Application filed May 5, 1921. Serial No. 466,957.

This invention relates to carburetors for internal combustion engines for motor vehicles which carburetors are provided with offset fuel chambers and fuel nozzles or passages extending above the level of the fuel therein, and its object is to provide an apparatus of this character in which the heavy particles of fuel will be intercepted and in which the richness of the fuel may be closely controlled.

This invention consists in a carbureting device having an outlet passage of standard size extending from the carbureting chamber in which the throttle valve is mounted, the net cross-sectional area of the carbureting chamber at the throttle shaft being equal to that of the outlet opening, and the carbureting device having a shoulder at the plane where the discharge passage connects to the carbureting chamber.

It also consists in the details of construction illustrated in the accompanying drawing and particularly pointed out in the claims.

In the drawing, Fig. 1 is a side elevation of a carburetor embodying this invention. Fig. 2 is a central vertical section thereof.

Similar reference characters refer to like parts throughout the several views.

The body of the carburetor is formed with an air-intake passage 2, a float chamber 3, a mixing chamber 4 in which is mounted a throttle valve 5 on a shaft 6 and a fuel outlet passage 7 surrounded by a flange 8. The float chamber has a removable cover 9 and a float 10 therein is attached to the lever 12. Screwed into the top of the float chamber is a sleeve 13 which is provided with a seat (not shown) for a valve 14 of any well known design, a small chamber 15 being mounted on the upper portion 16 of this sleeve and having a fuel supply connection 17. The screw 18 holds this chamber 15 and the fuel screen 19 in position. A wall 23 separates the air passage 2 from the float chamber. This construction forms no part of the present invention.

A fuel passage 20 extends along the bottom of the float chamber and has an intake opening 21 above the bottom thereof. The boss 22 at the opposite end of this passage receives the bushings 24 and 25, the former supporting the needle valve 26 and the latter the fuel nozzle 27 which is of such length that the carburetor may be inclined through as great an angle as that of the steepest hill,

seldom over thirty degrees, which the motor vehicle can negotiate, without the fuel flowing from the top of the nozzle. This angle will be less than that of the line X—X drawn in Fig. 2.

The nozzle extends up into the venturi consisting of a collar 28 having a downwardly tapering passage 29 which ends at a flange 30, which collar is supported by the posts 32 connected by a ring 33. Slidable on the collar 28 and legs 32 is an air valve consisting of a cylinder 34 and perforated top 35. Depending from the top is a hub 36 having a central opening 37 in alignment with the fuel nozzle.

A stem 38 is slidable through the bottom of the air-intake passage and is normally held down by the spring 39, and this stem connects to a valve 40 slidable on the fuel nozzle 27. An arm 41 on the outside of the air-intake passage connects to the arm 42 within this passage and this second arm extends beneath the curved upper end of the stem 38. Substantially no air can pass through the space between the nozzle and the inner wall of the valve 40.

The fuel outlet passage 7 is smaller in diameter than that portion 43 of the mixing chamber 4 through which the shaft 6 extends, so that this lower portion 43 will have as large an effective area as the outlet 7. I have found that a carburetor has greater fuel capacity when the area of the passage by the throttle shaft 6 is as large as the area of the outlet 7. This outlet 7 could be bored out to the same diameter as is the passage 43 without loss of fuel capacity, but the industries have standardized the size of the outlet flange 8 of the different sizes of carburetor, and it is, therefore, not practical to properly match such bored out carburetors to the standard flanges and gaskets, and besides, they would also be quite likely to leak air at these improperly made joints. I also have found at certain low speeds, on some motors, a decided increase of power can be obtained by use of the annular shoulder 44, and that this advantage is secured by having this shoulder at substantially any point between the throttle and the point where the intake manifold branches. The probable reason is that the heavy fuel globules strike against this shoulder 44 and are broken up.

The opening within the flange 30 may be closed by the top of the spool 40 when that

is slid up by the arm 41, which reduces the air supply which may flow up around the nozzle 27 and creates a greater suction at the discharge end of the fuel nozzle. In other words, the usual choke action is obtained by swinging the arm 41. The air valve 34 remains in its normal position and forces all the air to pass through the aperture in the flange 30 and around the nozzle so long as the engine is running at moderate speeds, but when the throttle 5 is opened sufficiently to cause enough suction to lift the air valve, the air will in part flow out laterally between the posts 32 and not pass the discharge end of the fuel nozzle. This will cause the explosive mixture to become much leaner for the higher speeds of the engine.

Accidents have occurred because of light farm tractors tipping over backward when pulling on mired plows and other heavy loads, the tractor wheels standing still and the machine simply winding itself up around the axle. To prevent this the intake 21 of the fuel passage 20 is so positioned that when the carburetor is inclined until the line X-X of Fig. 2 is horizontal, the intake 21 will be entirely above this line. This line indicates approximately the fuel level when the carburetor is thus tilted and is a greater angle than the steepest hill the vehicle can climb. But this angle is hardly half that at which the tractor tips over backward, and as the upward swing of the vehicle is always slow, the fuel supply to the engine is cut off before the dangerous angle is reached.

The details of construction and the proportions of the several parts of this carburetor may all be varied by those skilled in the art without departing from the spirit of my invention as set forth in the following claims.

I claim:

1. In a carburetor, a carbureting chamber and a ring at the lower end thereof, a plurality of posts extending upward from said ring and a collar at the upper ends of the posts, said collar having a downwardly tapering central passage and an inwardly extending flange at the lower end thereof, an air valve slidable on the collar and comprising a cylindrical shell fitting around the collar and posts and a perforated head at the upper end of the shell, a fuel nozzle extending upward above the flange in the collar, and a second valve slidable relative to the fuel nozzle to reduce the effective opening in said collar.

2. In a carburetor, in combination, a fuel mixture outlet passage, a mixing chamber, a circular plate throttle and a shaft therefor in the mixing chamber, the effective cross sectional area of said mixing chamber at the throttle shaft being substantially the same as that of the fuel mixture outlet passage, said carburetor being formed with an annular shoulder extending at substantially right angles to the flow of the fuel mixture and located at the discharge side of said throttle.

3. In combination, a carburetor body having an air inlet and a plurality of air passages connecting thereto and to the outlet for the fuel, one of said passages being central and axial with the body of the carburetor and other passages extending radially therefrom; a fuel nozzle extending axially of said central passage, a valve slidable on the nozzle and adapted to vary the effective area of said central passage, and means controlled by the flow of air through the central passage to regulate the flow of air through said radial passages.

CHESTER F. JOHNSON.
